UNITED STATES PATENT OFFICE.

CHARLES DOERING, JR., OF CHICAGO, ILLINOIS.

STIRRING OR AGITATING DEVICE.

989,342.

Specification of Letters Patent. Patented Apr. 11, 1911.

Application filed September 17, 1909. Serial No. 518,280.

To all whom it may concern:

Be it known that I, CHARLES DOERING, Jr., citizen of the United States, residing at Chicago, in the county of Cook and State 5 of Illinois, have invented certain new and useful Improvements in Stirring or Agitating Devices; and I do hereby declare the following to be a full, clear, and exact description of the invention, such as will enable others skilled in the art to which it 10 appertains to make and use the same.

This invention relates to a novel construction in a stirring or agitating device for receptacles, such as paint cans and barrels, the 15 object being to provide a simple and efficient device of this character which can be inserted into a can or barrel through the opening usually provided therein, and which by being subsequently revolved will 20 serve to agitate and stir the contents thereof to properly readmix the solids and liquids, and consists in the features of construction and combinations of parts hereinafter fully described and claimed.

25 In the accompanying drawings illustrating this invention: Figure —1— is a central vertical section of a can equipped with a stirring device constructed in accordance with my invention, the same being shown 30 in this figure as partly inserted and the stirring blade in its vertical position. Fig. —2— is a similar section showing the device completely inserted and the stirring blade disposed in its horizontal position. 35 Fig. —3— is a view similar to Fig. —2— showing a modified form of construction. Fig. —4— is a detail illustrating the manner of connecting the shaft to the stirring blade.

40 In all cases where liquids contain solids in suspension, as in paint, the solids usually settle to the bottom of the receptacle and before use of the contents of the latter the same must be thoroughly stirred so as to 45 again mix solids and liquid to hold all of the former in suspension in the liquid. Paint cans are usually provided only with a stoppered opening and barrels are provided only with the usual bung hole. The small 50 area of the opening thus provided renders difficult and almost impossible the proper stirring of the contents so as to restore the same to the relative conditions pertaining at the time the can or barrel is filled, the 55 stirring most generally being accomplished

by means of a stick inserted through the opening and which is rotated in the can in order to stir the contents. The stick is an inadequate instrument for the purpose and usually leaves a part of the contents of the 60 can adhering to the walls and bottom of the same so that only a part instead of all of the solid contents becomes admixed with the liquid. In many cases the variation in quantity of solids in proportion to liquid 65 is detrimental and even fatal to the attainment of the object for which the compound is intended.

The object of my invention is to provide a stirring and agitating device which can 70 be inserted into the small opening provided in the receptacle and which after insertion affords ready means of access to every part of the walls and bottom of the can for the purpose of scraping off the solid matter and 75 admixing the same with the liquid, and furthermore to afford greater ease of operation during the stirring of such contents. To this and other ends my invention comprises a vertical shaft consisting of two 80 semi-cylindrical portions A and B respectively, which when opposed form a cylindrical shaft, the two portions of which are longitudinally movable relatively to each other. The upper end of the part A is bent 85 to form a crank C by means of which the shaft is rotated and the part B terminates at its upper end in a hook D by means of which said part B is moved longitudinally 90 relatively to the part A.

The lower end portions F and G of the parts A and B of the shaft are offset outwardly from each other so as to provide a free space therebetween, one of said end portions, as for example the part F, being also 95 slightly bent laterally for reasons which will hereinafter appear. Each of said offset portions F and G is pivotally secured at its lower end to a blade H which preferably is equal in length substantially to the diameter 100 of the receptacle, and is provided with perforations I and bifurcated ends J for the purpose of increasing its efficiency as a stirring and mixing device. The pivotal connections K and L are relatively offset from one another horizontally of the blade H so that upon imparting relative vertical movement to the parts A and B the said blade H will be turned from a horizontal to a vertical position or vice versa, the pivot L being dis- 105 110

posed at a lower elevation than the pivot K when the blade is disposed in its horizontal position.

Longitudinally movable on the shaft

5 A—B is a stopper member M which performs two functions, to wit: It constitutes a bearing for said shaft and at the same time forms a stopper for the opening in the receptacle.

10 In use the device is first inserted into the can or receptacle while the parts are disposed in the position shown in Fig. —1— and after the uppermost end of the blade H has passed below the opening in the receptacle the part B of the shaft is moved downwardly relatively to the part A thereby turning said blade H to a horizontal position. The bearing M is then firmly inserted in the opening in the receptacle and the 15 shaft A—B is now rotated by means of the crank G. Said shaft A—B being longitudinally movable in the bearing M may be raised and lowered while being rotated so as to cause said blade H to work at different elevations. Where the matter to be stirred is very heavy, as in the case of paint, it becomes necessary to begin operations near the top of the settled mass of solid matter and gradually work downwardly to the lower 20 elevations thus attaining a thorough read-mixture of the solid and liquid contents of the receptacle in the proportions pertaining at the time that said contents were introduced into the receptacle. After thoroughly 25 stirring the contents of the receptacle, the said device may be removed by returning the parts A—B to the relative positions shown in Fig. —1— or said stirring device may remain in place in the receptacle and only the bearing M removed when it is desired to discharge a part of the contents.

In Fig. —3— I have illustrated a modified form of construction in which a tube N is used in place of the two-part shaft A—B.

45 Said tube is bifurcated at its lower end and in said bifurcated portion a blade O is received between its ends. The said blade O is pivotally secured, as at P, in any suitable manner and is provided with a projection Q having an opening therein to receive the lower end of a plunger R passing through said tube and by means of which said blade O is turned from vertical to horizontal position and vice versa, said plunger R being reciprocated relatively to the tube to accomplish this purpose. Secured to the tube N is a crank S by means of which the device is ro-

tated, said tube passing also through a bearing T which constitutes a stopper for the opening in the receptacle.

My said device is very simple and efficient and is also very cheap, and is intended for 60 use by all persons having frequent occasion to stir materials such as paint, etc., in which the solids heavier than the liquid settle to the bottom of the receptacle and render difficult the work of remixing the contents. 65

I claim as my invention:

1. The combination with a receptacle having a discharge opening, of a member fitting said opening, a shaft rotatable in said member consisting of two relatively longitudinally movable parts, and a single stirring blade pivotally secured at respectively different points between its ends to each of said parts and adapted to be swung from vertical to horizontal position and vice versa by relative longitudinal movement of said parts of said shaft. 70

2. The combination with a receptacle having a delivery opening, of a plug fitting said opening, a member rotatably and longitudinally movable in said plug, said member comprising two relatively longitudinally movable parts, a single stirring blade pivotally connected at respectively different points between its ends with each of said parts and adapted to be swung from vertical to horizontal position and vice versa by relative longitudinal movement of said parts of said member, and a crank on said member. 80

3. The combination with a receptacle having a delivery opening, of a plug fitting said opening, a member rotatably and longitudinally movable in said plug, said member comprising a split shaft the parts of which are relatively longitudinally movable, the 90 lower end portions thereof being offset from each other, a single stirring blade having pivotal connection at respectively different points between its ends with each of said parts and adapted to be swung from a substantially vertical to a substantially horizontal position and vice versa by relative longitudinal movement of said parts, a crank on one of said parts, and a hook on the other thereof. 100

In testimony whereof I have signed my name in presence of two subscribing witnesses.

CHARLES DOERING, JR.
